UNITED STATES PATENT OFFICE.

FRANK KNOBELOCH, OF DAYTON, OHIO.

PAPER BOX.

No. 834,142.

Specification of Letters Patent.

Patented Oct. 23, 1906.

Application filed December 19, 1902. Renewed November 27, 1905. Serial No. 289,345.

To all whom it may concern:

Be it known that I, FRANK KNOBELOCH, a citizen of the United States of America, and a resident of Dayton, county of Montgomery, 5 State of Ohio, have invented certain new and useful Improvements in Paper Boxes, of which the following is a specification.

My invention consists in the novel features hereinafter described, reference being had 10 to the accompanying drawings, which illustrate one form in which I have contemplated embodying said invention, and the invention is fully disclosed in the following description and claims.

15 Referring to the said drawings, Figure 1 is a plan view of the blank from which the box embodying my invention is formed. Fig. 2, Fig. 3, and Fig. 4 show the successive steps taken in folding up the blank to form the collapsed box. Fig. 5 is a perspective view of the expanded box. Fig. 6 is a plan view of the same, on a reduced scale. Fig. 7 is a sectional view taken on the line $z z$ of Fig. 5, showing the position of the bottoms in the 25 act of expanding the box just before the bottoms have been brought to their final position.

My invention relates particularly to folding paper boxes of trapezoidal form known 30 in the trade as "pail-filers," the dimensions of the said boxes being such that a number of the said boxes may be placed within a pail or other circular receptacle with their longer sides disposed radially thereto, so as to completely fill the circular space within such receptacle; and my invention has for its object 35 to form such a box from a blank, so that it may be folded flat for shipment and may be unfolded and placed in operative condition 40 when desired.

Referring to the drawings, Fig. 1 represents a plan view of the blank from which the box is made before folding, said blank being made of paper or cardboard of the desired thickness and cut and scored to form 45 the following parts.

A represents the exterior bottom section, which is of trapezoidal form and is provided with a diagonal score a , upon which it may 50 be folded.

B and C are the longer sides of the box, formed integrally with the bottom section A by extending its two longer edges. D and E are the two shorter sides of the box and are 55 integral with the sides B and C, respectively, being of the same height as said sides B and

C and of the same width as the shorter edges of the bottom section A.

F is the interior bottom section, which is of the same size as the exterior bottom section 60 A and is made integral with one of the short side sections D E, in this case the short side section D, and is scored diagonally from the outer corner of the side section D, as shown at f^2 , to enable it to fold substantially centrally. The interior bottom section F is also provided on its longer edges with flaps f and f' , which when the box is formed fold up 65 against the inner faces of the side sections B C and by contact therewith hold the bottom 70 section F firmly in position and also brace the sides B and C. The other short side section E is provided with a bottom locking-flap G, integral therewith at its bottom edge, as shown, which when the box is formed lies 75 between the exterior bottom section A and the interior bottom section F and is held by contact therewith, thus bracing the side section E, which is the only one not connected 80 integrally with one or the other of the bottom sections.

To form the box, it is necessary to unite the adjacent edges of sections B C and D E, one of the meeting edges being provided with a pasting-flap for the purpose. In this instance the sections B and D are each provided with a pasting-flap b and d , respectively. To form the box from this blank, the interior bottom locking-flap G is turned inward to lie upon the side section E, and the 85 interior bottom F is folded upon itself on line f^2 and is then folded upon the side section D. The side sections C and E are then turned over upon the sections B D, folding on the scored line a of exterior bottom A, 90 and the pasting-flaps b and d are pasted to the side sections C and E, respectively. Both 95 of these pasting-flaps are on the same side, as will be seen in the drawing, thus expediting the pasting operation, and it is only necessary to paste these two flaps.

In expanding the collapsed or folded box the sides B, C, D, and E are moved apart, thus raising the exterior bottom A into horizontal position. The bottom flap G is then 105 pushed down upon the bottom A, and the interior bottom F is then pushed down upon flap G and exterior bottom A, the lateral flaps $f f'$ thereof being bent upward and engaging the sides B and C.

110 It will be seen that the box has two bottom sections A and F, each of which forms a

- complete bottom for the box. The bottom A is integral with two sides B and C, and the bottom F is integral with one side D, thus firmly uniting the sides when the bottoms are 5 in operative position, and the side E which is not connected to the said bottoms is provided with the flap G, which is firmly held between the two bottoms and thus braces and secures the remaining side.
10. What I claim, and desire to secure by Letters Patent, is—
1. A blank for a collapsible box having side sections, a bottom section united to two sides, an auxiliary bottom section of the 15 same size as the main bottom section united to another side and adapted to fold upon the main bottom when the box is expanded, substantially as described.
  2. A blank for a collapsible box having 20 side sections, a main bottom section united to two of the side sections, an auxiliary bottom section of the same size as the main bottom section united to another side section and a bottom flap united to another side section 25 and adapted to lie between the bottom sections when the box is expanded, substantially as described.
  3. A blank for a collapsible box having side sections, a bottom section united to two 30 sides, an auxiliary bottom section of the same size as the main bottom section united to another side and adapted to fold upon the main bottom when the box is expanded, said auxiliary bottom section being provided 35 with lateral flaps to engage the side sections, substantially as described.
  4. A blank for a collapsible box having side sections, a main bottom section united

to two of the side sections, an auxiliary bottom section of the same size as the main bottom section united to another side section and a bottom flap united to another side section and adapted to lie between the bottom sections when the box is expanded, said auxiliary bottom section being provided with 40 lateral flaps to engage the side sections, substantially as described.

5. A four-sided collapsible paper box, having an interior and exterior quadrilateral bottom and two of whose sides are formed by 45 extensions of adjacent edges of one of said quadrilaterals, the second two sides being formed by extensions of the outer side edges of the first sides, and the other quadrilateral bottom projecting down from the bottom 50 edge of one of the second sides and a flap projecting down from the bottom edge of the other of said second sides, substantially as described.

6. A four-sided collapsible paper box, having an interior and exterior quadrilateral bottom, two of whose sides are formed by extensions of adjacent edges of one of said quadrilaterals, the second two sides being formed by extensions of the outer side edges 55 of the first sides, two glue-flaps, one upon the side edge of one of the first, the other upon the side edge of one of the second sides, and the other quadrilateral bottom projecting down from the bottom edge of one of the 60 second sides, substantially as shown and described.
